(57) **CLAIM**

The ornamental design for a display screen with animated graphical user interface for a project summary dashboard as shown and described.

DESCRIPTION

FIG. 1 is a front view of a first display of a display screen with animated graphical user interface for a project summary dashboard showing the new design;

FIG. 2 is a front view of a second image thereof;

FIG. 3 is front view of a third image thereof;

FIG. 4 is a front view of a fourth image thereof; and,

FIG. 5 is a front view of a second page thereof.

The broken lines in the drawings are for the purpose of illustrating portions of the graphical user interface and form no part of the claimed design. The outer broken lines showing a portion of the computer display screen form no part of the claimed design.

The appearance of the transitional image sequentially transitions between the images shown in FIGS. 1-5. The process or period in which one image transitions to another forms no part of the claimed design.

1 Claim, 5 Drawing Sheets
